OSCAR WOODWARD, OF BABYLON, NEW YORK, ASSIGNOR TO REMINGTON TYPE-WRITER COMPANY, OF ILION, NEW YORK, A CORPORATION OF NEW YORK.

TYPEWRITING-MACHINE.

1,380,455.

Specification of Letters Patent. Patented June 7, 1921.

Application filed January 3, 1920. Serial No. 349,192.

To all whom it may concern:

Be it known that I, OSCAR WOODWARD, citizen of the United States, and resident of Babylon, in the county of Suffolk and State of New York, have invented certain new and useful Improvements in Typewriting-Machines, of which the following is a specification.

My invention relates to typewriting machines and more particularly to tabulating mechanism therefor.

Heretofore in certain characters of column selecting mechanisms, the constructions were such that any desired column could be selected at will, but where the operator desired merely to use the tabulator to jump the carriage to successive columns, or from one column to the next throughout successive fields, it was necessary to operate the selecting keys successively, say, first, the "No. 1" selecting key for the first column, then the "No. 2" selecting key for the next column, and so on. This entailed on the operator remembering what selecting key was last operated, or an inspection of the work in each instance to determine the position of the next column to be selected, and then a selection and operation of the corresponding tabulator key. This resulted in confusing the operator, diverting the operator's attention from other aspects of the work in hand, and the loss of time that might advantageously be used in the production of more work, and sometimes in mistakes which caused further confusion and delay.

The main purpose of the present invention, generally stated, is to provide simple and effective means by which these difficulties may be overcome and a single one of the selecting keys preferably key Number 1, may be used continuously to jump the carriage successively from one column to the next, without, however, destroying the availability of the selecting mechanism to be used as such.

To the above and other ends which will hereinafter appear my invention consists in the features of construction, arrangements of parts and combinations of devices to be set forth in the following specification and particularly pointed out in the appended claims.

In the accompanying drawings wherein like reference characters designate corresponding parts in the various views,

Figure 1 is a fragmentary side elevation with parts in section of one form of typewriting machine embodying my invention.

Fig. 2 is an enlarged detail transverse sectional view of the stop bar and one of the column stops thereon.

Fig. 3 is a detail fragmentary rear perspective view on an enlarged scale of the stop bar and five column stops mounted thereon.

Fig. 4 is a transverse sectional view of the parts shown in Fig. 2, the section being taken on the line $x-x$ in said figure and looking in the direction of the arrow at said line.

Fig. 5 is a fragmentary detail rear perspective view of a modified form of stop and bar.

Fig. 6 is a detail transverse sectional view of the same on an enlarged scale.

Fig. 7 is a view corresponding to Fig. 6 but showing another modified form of stop construction.

I have shown my invention in the present instance embodied in a No. 10 Remington machine which includes column selecting mechanism of the character disclosed in the patents to G. A. Seib, Nos. 1,132,286 and 1,273,545, dated respectively Mch. 16, 1915 and July 23, 1918.

While the present invention is susceptible of embodiment in No. 10 Remington machines with but few and inexpensive changes it should be understood that the invention may be incorporated in other styles of typewriting and like machines.

I have shown in the drawings only so much of the No. 10 Remington machine as may be necessary to arrive at an understanding of my invention in its inclusion therein.

The frame of the machine includes a top plate 1 on which a carriage 2 is mounted to travel from side to side of the machine, the carriage carrying the usual cylindrical platen 3. Rearwardly projecting arms 4 are secured to the carriage near the ends thereof and support a column stop bar 5 formed with teeth 6 on opposite sides thereof.

Column selecting mechanism of the character shown in the above mentioned Seib patents, and similar to that employed in the No. 10 Remington machine, is provided to co-act with the column stops carried by the column stop bar 5.

The tabulator 7 is secured by screws 8 to the top plate of the machine and sup-

ports pivoted selecting levers 9 each of which terminates at its upper end in a forwardly extending finger 10 which co-acts only with its particular pivoted column selecting stop 11. It follows therefore that each column selecting key is operative to actuate the companion lever 9, and to project forwardly the particular selecting stop 11 with which said lever co-acts. The selecting stops 11 are arranged in different horizontal planes and each is adapted to swing forwardly on a pivot 11^a in a fixed path or invariable plane, which differs from the planes of movement of all of the other stops 11. This is effective to bring the projected stop 11 into co-operative relation only with the particular stop projection on the particular counter stop or column stop with which it is to co-act. Each of the column stops is designated as a whole by the reference numeral 12. These column stops are constructed somewhat like the column stops disclosed in the application of Elbert S. Dodge, 268,252, filed Dec. 26, 1918. Thus each stop is formed with a central body portion 13 bifurcated to receive and straddle the column stop bar. Two sheet metal side plates 14 are riveted at 15 on opposite sides of the body portion 13 of the stop. Each sheet metal plate 14 is bifurcated to straddle the stop bar, but the inner parallel walls 14^a of the plates extend inwardly farther than the body portion 13 of the stop, so that they may be received in the interdental spaces between the teeth 6 on the stop bar. Each stop is provided with a finger piece 16 and with a suitable detent to retain the stop against accidental displacement from the bar. In the present instance this detent is in the nature of a ball 17 which is received in a socket or aperture 18 formed in the body portion 13 of the stop, either at the forward side thereof as shown in Fig. 2, or at the rear side thereof as shown in Fig. 6. Each ball is pressed toward the column stop bar by a coiled expansion spring 19 which bears at one end against the ball and at its opposite end against a set screw 19^a threaded into a tapped portion of the opening 18. Each spring 19 thus exerts a force on the ball to cause it to bear against the lower corners of the adjacent teeth 6 on the column stop bar and thus prevent an accidental displacement of the stops from the bar. The stops may, however, be readily detached from the bar and reversed thereon or adjusted to different points along the bar. It will be understood that the inner end of each recess or opening 18 which receives a ball 17 is slightly contracted in order to limit inward movement of the ball contained therein.

Projecting from the body portion of each stop 12 at one side thereof, is an engaging member or arresting projection, portion of

contact. These projections or contacts are arranged in different horizontal planes, each having a different path of movement corresponding to the fixed plane of movement of its coacting selecting stop 11. In order that these contacts or projections on the column stops may be clearly distinguished in the drawings I have designated them by separate reference characters 20, 20^a, 20^b, 20^c and 20^d. It will be seen from the foregoing that an operation of the highest selecting stop 11, by its associated key (not shown), results in moving said selecting stop into the path of the projection 20^a on the right-hand column stop, as the parts appear in Fig. 3, said selecting stop 11 being ineffective on all the other column stops. So it is with each of the other column selecting stops, each being co-operative only with the particular column stop with which it is supposed to coact. With this arrangement it is necessary, should the operator desire to move successively from one column to the next, to operate the selecting keys successively in the one, two, three order as hereinbefore pointed out.

In order to avoid the confusion which may result in using the tabulator to jump the carriage to successive columns in the manner described, I have provided each column stop with an additional stop projection, engaging member or contact 21 which projects in the opposite direction from the stop projections hereinbefore described, or from the opposite side of the body portion 13 of the stop member. These stop projections or contacts 21 are all arranged in the same plane or in one line, all having the same path of movement. In the construction shown in Figs. 1 to 4, inclusive, the stop projection 21 is arranged at the top of the stop, at a height corresponding to the stop projection 20^a so that when the column stops are detached and reversed on the stop bar 5 all of the projections 21 will be arranged so that they may coact with the uppermost selecting stop 11. It follows therefore that repeated operations of a single key, say the "No. 1" key, which controls the uppermost selecting stop 11, will result in the carriage moving successively from one column field to the next with the aid of this single key.

In the construction shown in Figs. 5 and 6 it is unnecessary to detach the column stops and reverse them in order to bring the aligned projections into use. In this modified form of construction parts which correspond to those previously described will be designated by the same reference characters. The column stop bar 5^a, as shown in Fig. 5, is pivoted at one end, as at 22, to its supporting member or section 23, which in turn is supported by one of the arms 4 of the carriage. A locking flange 24 is secured to the stop bar and is provided with two re-

cesses 25 on opposite sides thereof. A locking latch 26 is pivoted at 27 on the supporting member and has a locking projection 28 at one end thereof which is adapted to be received in either of the recesses 25 in the locking flange and lock the bar against turning movement. A coiled expansion spring 29 is interposed between the outer end of a locking latch and the supporting member 23 in order to maintain the latch in its locking position. The opposite end of the stop bar is pivoted to a supporting member corresponding to the member 23 in a like manner. In this modified form of construction the additional projection or arresting portion 21^a on each of the column stops is situated at the lower end of the stop, instead of at the upper end thereof as in the previously described construction, all of the projections 21^a being in the same line. By releasing the locking latch 26 and giving the bar a half turn from the position shown in Fig. 5, all of the stop projections 21^a will be brought to a position corresponding to that previously occupied by the projection 20^a. All of the projections 21^a will therefore, be positioned to coat with the uppermost selecting stop 11 controlled by the "No. 1" selecting key. The advantage of this modified form of construction is that it is unnecessary to detach the column stops from the bar in order to bring either one set or the other set of stop projections into use.

From the foregoing description it will be seen that each of the key controlled stops 11 is moved in an unvariable fixed path; that the contacts thereon are so arranged that each contact is cut by a different one of a series of longitudinal parallel lines or planes that extend transversely of the machine or in the general direction of the travel of the carriage; and that the selectable stepped contacts 20, 20^a, 20^b, 20^c and 20^d on the reversible duplex column stops are arranged to move in parallel paths and in accordance with the arrangement of the contacts on the key controlled stops 11. It will also be observed that each contact 20, 20^a, etc., has a separate path of movement, whereas the other series of contacts 21 are uniformly arranged on their stops in a single line and travel only in a single path.

While I have shown five selecting stops and five coating column stops, it will be understood that the number of such stops employed may be varied. It is sometimes found desirable to employ two or more complete sets of column stops, for use with the single set of selecting stops of the character described. In such an instance each set of column stops is a duplicate of the set shown.

Various other changes may be made without departing from the scope of my invention. For instance the stops could be pro-

vided with projections 21^b located as shown at Fig. 7 when only a quarter turn of the rod or stop bar would be necessary to bring all of said aligned stops to a position to engage the upper stop 11.

What I claim as new and desire to secure by Letters Patent, is—

1. In a typewriter machine, the combination of a series of key controlled stops each having its contact movable only in a single fixed unvariable path, and a series of counter stops provided with two series of engaging members or arresting portions one series arranged for column selection and the other arranged for column-to-column work only, all of said members of the column-to-column series coacting with the contact on a single one only of said key controlled stops for column-to-column work, and the said members of the other series each coacting only with the contact of its own individual key controlled stop for column selection work.

2. In a typewriting machine, the combination of a series of key controlled selecting stops movable in different planes and each movable in an invariable plane, a series of counter stops provided with two series of engaging members or arresting portions, the members of one series being arranged in a single plane for coöperation with but a single one of said selecting stops, the members of the other series being arranged in different planes corresponding to the different planes in which the selecting stops are located and each coacting only with a given one of said selecting stops, and means for bringing the engaging members of either series into position for use.

3. In a typewriting machine, the combination of a carriage, a series of key controlled stops the contacts of which are so arranged that each contact is cut by a different one of a series of parallel lines that extend transversely of the machine or in the general direction of the travel of the carriage, a series of coating adjustable column stops each provided with two contacts, one series of contacts on the column stops being arranged to move in parallel paths corresponding to the arrangement of the contacts on the key controlled stops, the other series of contacts on the column stops being arranged in a single line to travel in a single path, and means which enable the column stops to be shifted so that either series of contacts may be presented for use and the other series rendered ineffective, whereby in accordance with one arrangement of the column stops the column selecting keys may be used to select any desired column and in accordance with the other arrangement the carriage may be caused to move always successively from one column to the next.

4. In a typewriting machine, the combination of a carriage, and tabulator mechanism

4

for arresting the carriage, said tabulator mechanism including a series of stops each provided with two engaging members or arresting portions on different sides thereof, 5 all the engaging members on one side having a single path of movement when in use, the other members having different paths of movement one from the other, and means for enabling said stops to be shifted to 10 bring the engaging members on one or the other side thereof into use.

5. In a typewriting machine, the combination of a carriage, a column stop bar carried thereby, column stops carried by said bar 15 and each provided with contacts on opposite sides thereof, a series of contacts on one side of the stops constituting selective contacts which move in different paths each of such contacts having a separate path of 20 movement, and the series of contacts on the opposite sides of the stops all moving in a single path, a series of key controlled column selecting stops each movable in an unvariable fixed path and the contacts on which 25 are arranged according to paths of movement of the selectable contacts on the column stops, and means for bringing either series of contacts on the column stops into use and for enabling the column stops to be adjusted to different points along the column 30 stop bar.

6. In a typewriting machine, the combination of a carriage, and tabulator mechanism for arresting the same, said tabulator mechanism comprising a series of key controlled selecting stops each movable always in a single fixed unvariable path which differs from the paths of movement of all of the other selecting stops, a column stop bar, and 10 a series of column stops mounted for individual adjustment to different points along said bar, each column stop having two arresting projections thereon, one series of said arresting projections being variably 15 positioned on the stops according to the variations in the paths of movement of the key controlled stops, so that each will coat only with a given one of the selecting stops, whereas the other series of projections are 20 all positioned in a single line so that they may all coat with a single one only of the selecting stops.

7. In a typewriting machine, the combination of a carriage, and tabulator mechanism 55 for arresting the same, said tabulator mechanism comprising a series of key controlled selecting stops each movable always in a single fixed path which differs from the paths of movement of all of the other select-

ing stops, a column stop bar, a series of column stops on said bar, each column stop having two arresting projections thereon, one series of said arresting projections being variably positioned on the stops so that each will coat only with a given one of the selecting stops, whereas the other series of projections are all positioned in a single line so that they may all coat with a single one only of the selecting stops, and means which enable either series of projections to be brought into use.

8. In a typewriting machine, the combination of a carriage and tabulator mechanism for arresting the same, said tabulator mechanism comprising a series of key controlled selecting stops each movable always in a single fixed path which differs from the paths of movement of all of the other selecting stops, a series of column stops each provided with two arresting projections on different sides thereof, one series of such projections being variably arranged on the stops according to the variation of the positions of selecting stops, so that each of these projections will coat only with a given one of the selecting stops, whereas the other series of projections are all arranged in a single line so that they may all coat with a single one only of the selecting stops, and means for enabling the column stops to be turned to bring either series of projections into use, whereby the mechanism may be used as a column selector to select any desired column, or may be used to cause the carriage to jump from one column to the next always with the aid of the same key.

9. In a typewriting machine, the combination of a carriage having a column-stop support, a set of reversible duplex column stops thereon, one side of said set of stops having a series of contacts in stepped arrangement and the other side of said set of stops having contacts all arranged in a single straight row, a set of key controlled column stops adapted to cooperate with either the series of stepped contacts or the series of straight row contacts, according to which series of contacts is adjusted to coat with the key controlled stops.

Signed at the borough of Manhattan, city of New York, in the county of New York and State of New York this 31st day of December A. D. 1919.

OSCAR WOODWARD.
